UNITED STATES PATENT OFFICE.

STARR TRUSCOTT, OF BIRMINGHAM, OHIO.

AIRPLANE.

Application filed May 8, 1919. Serial No. 295,740.

To all whom it may concern:

Be it known that I, STARR TRUSCOTT, a citizen of the United States, and resident of Birmingham, in the county of Erie and State of Ohio, have invented new and useful Improvements in Airplanes, of which the following is a specification.

The present invention relates to airplanes, and more particularly to the wing or plane and frame construction thereof.

The prevailing practice in constructing the wings or planes of airplanes, is to secure transverse ribs to longitudinal spars, of which there are usually two, and to stretch fabric or other pliant material across the upper and lower edges of the ribs, whereby the pressure and strains imposed against the fabric is transmitted to the ribs and thence to the longitudinal spars. This results in an uneven distribution of the stresses and strains, and a plane or wing of such construction has its maximum strength transversely thereof between its forward and rear edges thereof, instead of longitudinally in which direction the frames extend, because the longitudinal spars or members must take up all of the strains imposed on the ribs from the fabric. Consequently, the spars must be of great strength to resist the strains and pressure resulting from the air pressure, and the bars are therefore the vital members of the framework of the planes or wings.

The object of the present invention is to improve the wing or plane construction, by utilizing a stiff or rigid shell or skin, such as ply wood, sheet metal, or the like, instead of the usual pliant fabric, in order that the shell will provide a large factor of strength in itself, as compared with the shell of a steel ship, with longitudinal ribs or members within the shell to take up the strains therefrom direct, said ribs or members being of light construction and distributed in a comparatively large number transversely of the wing or plane between its front and rear edges, as contradistinguished from the use of the spars now employed. The present construction also includes transverse braces at longitudinally spaced points in order to reinforce and stiffen the wing or plane trans-

versely, said braces intersecting the longitudinal ribs to make the framework or skeleton structure more rigid, but the strains and stresses are taken up by the shell and longitudinal ribs direct. By thus providing a stiff or rigid shell with a relatively large number of longitudinal ribs therein, the wing or plane will have maximum strength in a longitudinal direction as required, and the construction will take up the pressure and strains uniformly throughout without the excessive stresses and strains existing at certain points as in the ordinary construction. With the present arrangement, the wing or plane is of substantially uniform strength throughout its area, so as to avoid or reduce to a minimum the tendency for the wing or plane to buckle or break, and at the same time, obtaining the results without materially sacrificing the lightness in weight of the construction.

A further object is to provide a novel assemblage of the shell, longitudinal ribs and transverse braces in order that portions of both the ribs and braces can be continuous across the points of intersection, and to provide other features of strength.

Another object is to provide struts for the planes or wings embodying some of the features thereof, viz., a stiff shell with enclosed longitudinal ribs, providing a light rigid construction instead of using the ordinary solid struts.

With the foregoing and other objects in view which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:—

Figure 1 is a plan view of a portion of the planes of an airplane, portions of the shell being broken away to show the skeleton framework.

Figure 2 is a front view thereof.

Figure 3 is an enlarged cross section of the wing or plane taken on the line 3—3 of Figure 1.

Figure 4 is a still further enlarged view of a portion of the section shown in Figure 3, to illustrate the details more clearly.

Figure 5 is a section taken on the line 5-5 of Figure 1 showing the aileron.

Figure 6 is an enlarged longitudinal section in detail, similar to Figure 4.

Figure 7 is a horizontal section through the intersection of a rib and brace.

Figure 8 is an elevation of one of the improved struts.

Figure 9 is a cross section taken on the line 9-9, of Figure 8.

Figure 10 is a similar cross section showing a modified form of strut.

Figures 11 and 12 are sections corresponding with the section shown in Figure 4, and showing modifications.

The present improvements can be used in planes or wings of various forms and Figures 1 and 2 illustrate one half of the spread or length of the biplane construction, in which the wings 4 are detachably connected to the central sections 2. The wings 25 1 have the ailerons 3 as usual.

Referring in detail to one wing or plane section 1, the same comprises a shell or skin 4 composed of ply wood, sheet metal, or other stiff or rigid material, and is of the usual form, as seen in Figure 3, being hollow and having suitably curved upper and lower surfaces. By using the stiff or rigid sheets of wood, metal or other suitable material, the shell or skin of the plane will constitute one of the main factors of strength instead of the skin being pliant as usual and requiring stretching and treatment to withstand the wind pressure, but not providing any appreciable strength or rigidity as in the present construction.

Within the shell or skin is a skeleton frame work to reinforce and cooperate with the shell to stiffen and strengthen it with as light a construction as practical. This frame work or reinforcing skeleton is composed primarily of longitudinal ribs arranged at intervals between the front and rear edges of the plane. Said ribs are light in construction and they are relatively close together, as seen in Figure 3, whereby the frame work is distributed throughout the area of the plane to uniformly take up the pressure and strains. The frame work shown in Figures 3 to 7, inclusive, is shown as constructed of wood, in which event the longitudinal ribs embody longitudinal cleats or strips 5 at the upper and lower edges thereof extending continuously from one end of the wing or plane to the other, and cemented or otherwise secured to the upper and lower sheets of the shell. Each rib also includes a series of vertical longitudinal webs 6 of ply wood, or the like, having their upper and lower edges seated and secured within grooves in the cleat 5, thus provid-

ing a light rigid construction of a cross section similar to an I-beam. The webs 6 can be provided with openings 7 therein to lighten them in weight, and vertical strengthening or bracing strips 8 can be cemented or otherwise secured to the webs 6 to increase the strength thereof.

The skeleton frame of the wing or plane also includes, at suitably spaced longitudinal points thereof, transverse braces, corresponding to the ordinary ribs but they can be fewer in number, owing to the stiffness of the shell 4 and the provision of the relatively large number of longitudinal ribs which take up the strains. These braces are used to brace the ribs and shell transversely the required amount, especially where the struts are attached to the wings. Each of the transverse braces includes a vertical web 10 of ply wood, or the like, extending continuously from one edge of the shell to the other, although it may be stated at this point, that some of the braces need not extend completely across the plane or wing when it is only required to brace a portion of the wing, such as the rear edge portion, when shorter braces can be used. The brace also has upper and lower cleats or strips 9 similar to the cleats 5 and grooved to engage the upper and lower edges of the web 10. The ribs and braces intersect, as seen in Figure 7; it being noted that the longitudinal cleats 5 are continuous, while the webs 10 of the braces are continuous from end to end of the braces, and the webs 6 of the ribs are discontinuous or divided, with their ends terminating adjacent to the webs 10. The cleats 9 of the braces are also discontinuous or divided so that their ends terminate adjacent to the cleats 5. In this manner, the cleats 5 which are secured to the sheets of the shell, to stiffen same, are continuous longitudinally, while the webs 10 of the transverse braces are also continuous, thereby providing for strength in both directions, and avoiding complete division of either the ribs or braces. The upper and lower edges of the webs 10 are provided with notches 11 for the passage of the cleats 5, so that said cleats can pass across the edges of the webs 10. The webs 10 can be provided with openings 12 for lightening the weight thereof, and the ends of the webs 6 of the ribs are seated and secured within the grooves of vertical cleats or strips 13 secured to the opposite side of the webs 10, as seen in Figure 7. The ribs and braces in thus intersecting one another and being secured together, will provide a thoroughly rigid frame work or skeleton, and in connection with the stiff shell or skin secured to the upper and lower edges of the longitudinal ribs and transverse braces, the wing or plane will have the strength required, being of lattice work. The webs 10 will maintain

the shape of the wing or plane transversely thereof, while the longitudinal ribs in combination with the inherent rigidity of the shell, will render the wing or plane of great strength longitudinally, both for compressive and bending strains. The forward and rear edges of the upper and lower sheets of the shell 4 converge together and are preferably stiffened and reenforced by suitable strips 14 to prevent fraying of the edges of the plane.

The present plane or wing construction is of especial advantage in larger planes or wings although it can be used in the smaller ones, but may be slightly heavier in weight than the ordinary construction in smaller airplanes. It is possible to have the ribs and braces intersect in just the reversed manner. Thus, referring to Figure 7, the numeral 10 can represent a continuous longitudinal web, and the numeral 6 a broken and divided web of a brace with the cleats constructed accordingly.

The aileron 3 can also be constructed in accordance with the wings being provided with a stiff shell and a suitable reenforcing skeleton therein.

When the wings are detachable, as seen in Figures 1 and 2, the adjacent ends of the ribs of the wing 1 and central section 2 of the plane can be detachably connected, by suitable joints 15, thus providing connections between each rib of the wing and the corresponding rib of the section 2 which is of similar construction. This feature, however, the same as other details are arbitrary and can be changed to suit conditions.

With the present construction of the wings or planes, it is desirable to use a similar construction of the struts 16, instead of using the solid struts as now employed. As shown in Figures 8 and 9, the strut 16 is composed of one part of relatively great width, instead of using individual front and rear struts, and the strut 15 has the forward and rear portions 17 merging at their upper and lower ends into the yokes 18 and are suitably secured to the planes. The strut 16 thus has a central opening, and it is composed of a shell or skin 19 of material similar to that used for the shells 4 of the planes, with vertical or longitudinal ribs and transverse webs 22 secured within the shell to reinforce the same. These ribs embody the cleats 20 secured to the sheets or sides of the shell 19, and webs 21 having their edges secured to the cleats 20, similar to the constructions of the ribs and braces above described. The strut 16 is therefore composed of a hollow rigid shell with interior stiffening ribs, thus providing a strong light construction. The webs stiffen the struts against sidewise strains, and the strut being relatively wide will have considerable strength transversely of the planes, as will

be apparent. The portions 17 of the strut can be of a cross section similar to that used in the ordinary struts, as seen in Figure 9.

Instead of having the struts composed of the front and rear portions 17, it can be solid from edge to edge as illustrated by the modified form of strut 16' shown in Figure 10. This eliminates the hole or opening in the strut and makes the sides thereof continuous from the forward to the rear edge. 75

Figures 11 and 12 illustrate details that can be used when sheet metal is employed for the plane or wing construction. Thus, longitudinal angle members 5' can be used to secure the edges of the webs 6 to the shell 4, and angle members 9' used between the webs 10 and shell instead of using the cleats as described above. Figure 12 shows channel members 5'' secured to the upper and lower sheets of the shell for the connections of the webs 6'' of the ribs, and the braces also embody members 9'' of channel or other suitable cross section. Instead of using sheet for the webs of the ribs and braces, lattice construction can be used, as shown by the oblique crossing brace members 10''. This lattice construction of the webs is especially useful in larger planes wherein the upper and lower sheets of the shell are spaced apart a considerable distance to render the use of lattice work practical. 95

Having thus described the invention, what is claimed as new is:—

1. An airplane wing comprising a shell of wood, metal or similar stiff material constituting a main factor of strength of the wing, and longitudinal stiffening ribs within said shell at close intervals between its edges and constituting strips secured to the shell and web portions secured to said strips. 100

2. An airplane wing comprising a shell having upper and lower sheets of wood, metal or similar stiff material constituting a main factor of strength of the wing, and longitudinal stiffening ribs arranged at close intervals between the longitudinal edges of the shell and embodying strips secured to said sheets and web portions secured to said strips. 110

3. An airplane wing comprising a shell having upper and lower sheets of wood, metal or similar stiff material constituting a main factor of strength of the wing, longitudinal stiffening ribs within the shell and arranged at close intervals between the longitudinal edges thereof, and transverse braces intersecting said ribs at longitudinaly spaced points of the wing, said ribs and braces having vertical webs secured to said upper and lower sheets. 115

4. An airplane wing comprising a shell having upper and lower sheets of wood, metal or similar stiff material constituting a main factor of strength of the wing, longitudinal stiffening ribs within the shell and 130

- arranged at close intervals between the longitudinal edges thereof, and transverse braces intersecting said ribs at longitudinally spaced points of the wing, said ribs and 5 braces having vertical webs, and strips secured to the upper and lower sheets of the shell and to the edges of said webs.
5. An airplane wing comprising a shell having upper and lower sheets of stiff material, longitudinal stiffening ribs within the shell and arranged at intervals between the longitudinal edges thereof, and transverse braces intersecting said ribs at longitudinally spaced points of the wing, said ribs and 10 braces having vertical webs, and strips secured to the upper and lower sheets of the shell and to the edges of said webs, some of said strips being continuous across the edges of the webs which they intersect and the 15 other strips being discontinuous and some of the webs being continuous past the intersections and the others being discontinuous.
6. An airplane wing comprising a shell of stiff material, and a skeleton frame therein 20 embodying intersecting members having vertical webs and strips secured to the shell and the edges of said webs, the strips of the members which extend in one direction being continuous and the webs thereof divided, and 25 the strips of the other members being divided and the webs thereof continuous to pass between the sections of the webs of the aforesaid members.
7. An airplane wing comprising a stiff 30 shell, and a skeleton frame therein embodying intersecting members having webs and strips securing the edges of said webs to the shell, the strips which extend in one direc-
- tion being continuous and the others divided, the webs of the divided strips being 40 continuous and having notches for the passage of the continuous strips, and the other webs being divided.
8. An airplane wing comprising a rigid shell, and a skeleton frame therein embodying intersecting members having webs and strips securing the edges of the webs to the shell, some of the strips being continuous and the others divided at the intersections, 45 the webs of the divided strips being continuous and the others divided, and strips securing the ends of the divided webs to the continuous webs.
9. An airplane wing comprising a rigid shell and a skeleton frame therein embodying intersecting members secured to the shell, each of said members constituting a plurality of parts, said members extending in different directions and parts of the members 50 which extend in each direction being continuous and the other parts divided at the intersections with the continuous parts.
10. An airplane wing comprising a shell composed of upper and lower sheets of wood, metal or similar stiff material constituting a 55 main factor of strength of the wing, longitudinal stiffening ribs within the shell, and transverse braces intersecting said ribs, said ribs and braces being secured to said upper and lower sheets and all of them having continuous portions from end to end and other portions divided at the intersections.

In testimony whereof I hereunto set my hand.

STARR TRUSCOTT.
